United States Patent Office

Des. 191,241
Patented Aug. 29, 1961

191,241

HUMIDIFIER

Douglas W. Anderson, Palatine, and John W. Davies,
Chicago, Ill., assignors to HanksCraft Company, Reeds-
burg, Wis., a corporation of Wisconsin

Filed Feb. 12, 1960, Ser. No. 59,376

Term of patent 14 years

(Cl. D62—4)

FIG. 1

Des. 191,241

PAGE 2

FIG. 2

FIG. 3

FIG. 4

FIG. 5

FIG. 1 is a front perspective view taken from the right side of a humidifier embodying our new design;

FIG. 2 is a top plan view thereof on a reduced scale;

FIG. 3 is a front elevational view thereof as shown in FIG. 2;

FIG. 4 is a right side elevational view thereof as shown in FIG. 2; the left side not shown being substantially the same; and

FIG. 5 is a rear elevational view thereof as shown in FIG. 2.

The bottom of the humidifier is plain and unornamented.

We claim:

The ornamental design for a humidifier, substantially as shown and described.
